(57) **CLAIM**

The ornamental design for a fuel briquet, as shown and described.

DESCRIPTION

FIG. 1 is a perspective view of a fuel briquet showing the new design;

FIG. 2 shows a top view of the fuel briquet shown in FIG. 1; FIG. 3 is a front elevation view of the fuel briquet of FIG. 1; and,

FIG. 4 is a back elevation view of the fuel briquet of FIG. 1. The broken lines shown represent unclaimed subject matter and form no part of the claimed design.
